UNITED STATES PATENT OFFICE.

FREDERICK C. KAINER, OF CHICAGO, ILLINOIS.

GEARING FOR WASHING-MACHINES.

SPECIFICATION forming part of Letters Patent No. 699,185, dated May 6, 1902.

Application filed July 19, 1901. Serial No. 68,901. (No model.)

To all whom it may concern:

Be it known that I, FREDERICK C. KAINER, a citizen of the United States, residing at Chicago, in the county of Cook and State of Illinois, have invented certain new and useful Improvements in Gearing for Washing-Machines, of which the following is a specification.

This invention relates to improvements in gearing to be used for washing-machines, churning, and other devices where an oscillatory motion of the rubber or dasher is desired; and it consists in certain peculiarities of the construction, novel arrangement, and operation of the various parts thereof, as will be hereinafter more fully set forth and specifically claimed.

The principal object of my invention is to provide a simple and inexpensive gearing for converting rotary motion into oscillatory motion or for imparting reciprocating movement.

Other objects and advantages of the invention will be disclosed in the subjoined description and explanation.

In order to enable others skilled in the art to which my invention pertains to make and use the same, I will now proceed to describe it, referring to the accompanying drawings, in which—

Figure 1 is a plan view of a washing-machine and gearing therefor embodying my invention. Fig. 2 is a central vertical sectional view thereof. Fig. 3 is an enlarged plan view of the gearing detached from the machine, and Fig. 4 is a view in side elevation of the upper portion of the machine and the gearing.

Similar letters refer to like parts throughout the different views of the drawings.

A represents the box or tub of a washing-machine, which may be of any suitable size, form, and material, but preferably rectangular in shape, as shown in the drawings. The upper inner portion of the box A is provided with a ledge a, on which the lid or cover A' will rest. This lid or cover is hinged at one of its edges to the box, as shown in Fig. 1 of the drawings. Secured at one side of the box and overlapping its upper edge is a bracket B, on the upper surface of which are formed or

provided two lugs b, having lateral recesses, for the purpose presently to be explained. Journalled in a suitable bearing in the bracket B is the power-shaft C, on which is mounted 55 a crank-wheel C' and also a bevel-gear C².

Secured to the upper surface of the lid A' is a plate or casting D, which extends from that edge of the lid or cover adjacent to the bracket B to about the middle of the lid or 60 cover and has journalled vertically in said end an oscillatory shaft E, on the lower portion of which is secured a rubber or agitator E' of the ordinary or any preferred construction. On the upper portion of the shaft E is mounted 65 a spur-gear e, which is shown in Fig. 3 of the drawings as being mutilated, but which may be a complete gear. Journalled on the plate D near the end thereof adjacent to the edge of the box is a beveled gear F, which meshes 70 with the bevel-gear C² on the power-shaft. The bevel-gear F has a horizontally-projecting arm G, which carries a stub-shaft g, to which is pivotally secured one end of a rack-bar H, which bar is provided with gear-teeth 75 h on its lower surface near one of its edges to engage the teeth of the gear e and is formed near its other edge with a longitudinal slot h' for the reception and operation of the upper end of the shaft E, as is clearly shown in Fig. 80 3 of the drawings. That end of the plate D adjacent to the power-shaft is provided with two openings to receive the lugs b on the bracket. A locking-bolt L, formed with slots m, through which the lugs b will pass, is slidably mounted on the upper surface of the plate D or casting. One end of the bolt L is provided with an upturned portion l to be used in engaging and disengaging it from the catches or recesses of the lugs b on the bracket. 90

When it is desired to raise the lid, the bolt L may be drawn in the proper direction by means of the projection l thereon, so that it will be freed from the lugs b, thus unlocking the parts.

By rotating the crank-wheel C' it is evident that the bevel-gear F will be rotated through its engagement with the bevel-gear C² and, through the instrumentality of the rack-bar H, will cause the rubber or agitator E' to oscillate.

Having thus fully described my invention,

what I claim as new, and desire to secure by Letters Patent, is—

The combination with a power-shaft, of a beveled gear, an oscillatory shaft suitably journaled, a gear on said shaft, a beveled gear journaled to engage the first-named beveled gear, a slotted rack-bar pivotally connected

to the last-named beveled gear and engaging the oscillatory shaft and the gear thereon, substantially as described.

FREDERICK C. KAINER.
